STOCKING

Sophia Criaris Dovas, Pennsauken, N. J.

Application November 24, 1953, Serial No. 27,775

Term of patent 14 years

(Cl. D47—7)

To all whom it may concern:

Be it known that I, Sophia C. Dovas, a citizen of the United States, residing at Pennsauken, in the county of Camden and State of New Jersey, have invented a new, original, and ornamental Design for a Stocking, of which the following is a specification; reference being had to the accompanying drawing, forming a part hereof.

I claim:

The ornamental design for a stocking, as shown.
